Glennir J. Ney, of Lowell, Mass.

Assignor to

The Lowell Manufacturing Co. of same place.

Letters Patent No. 1551, dated March 18, 1862.

This schedule is referred to in these Letters Patent and making part of the same.

Be it known to all whom it may concern:

Be it known that I, Glennir J. Ney, of Lowell in the County of Middlesex and State of Massachusetts have originated and designed a new pattern for carpets or other fabrics, of which the following is a full, clear and exact description, reference being had to the accompanying drawings, making part of this specification.

Fig. A. in the centre is a group of three large leaves. Corners 1, 2, 3, 4, when matched form a group similar to A. in the centre.

Running between, and connecting the centre and corners are series of small blocks.

A large diamond shaped frame surrounds the centre figure A. The corners of this frame underlie small possets at the sides and ends of the design.

The remaining portions of the design are occupied by a ground work of regular figures.

The colors employed for the different portions of the design may be varied to suit the taste and wish of the manufacturer.

Glennir.

What I claim as my invention and desire to secure by Letters Patent, is the design or pattern, for carpets or other
